Primary Examiner — Freda S Nunn(74) *Attorney, Agent, or Firm* — Cantor Colburn LLP(57) **CLAIM**

The ornamental design for a cook top, as shown and described.

DESCRIPTION

FIG. 1 is a front perspective view of a cook top showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is an enlarged view of the encircled portion '8' in FIG. 5.

The broken lines illustrating portions of the cook top form no part of the claimed design.

The dot-dot-dash broken lines encircling portions of the claimed design in FIG. 5 and that are illustrated as an enlargement in FIG. 8 form no part of the claimed design.
